(57) **CLAIM**

The ornamental design for a moisture guard, as shown and described.

DESCRIPTION

FIG. 1 is a top perspective view of a moisture guard showing my new design.

FIG. 2 is a bottom perspective view of the moisture guard in FIG. 1.

FIG. 3 is an end view of the moisture guard in FIG. 1.

FIG. 4 is an opposite end view of the moisture guard in FIG. 1.

FIG. 5 is a top view of the moisture guard in FIG. 1.

FIG. 6 is a bottom view of the moisture guard in FIG. 1.

FIG. 7 is a left side view of the moisture guard in FIG. 1.

FIG. 8 is a right side view of the moisture guard in FIG. 1.

FIG. 9 is a top perspective view thereof, showing the moisture guard in FIG. 1 in a state of use; and,

FIG. 10 is an enlarged view of the moisture guard in FIG. 9, taken from portion '10' in FIG. 9.

The broken lines shown in FIGS. 9 and 10 represent environmental subject matter only and form no part of the claimed design.

The dash-dash lines circular symbol in FIGS. 9 and 10 merely represents a partially enlarged view only and forms no part of the claimed design.

The moisture guard is shown with a symbolic break in its length. The appearance of any portion of the moisture guard between the break lines forms no part of the claimed design.
